PORTABLE MATERIAL RECEIVING MEANS

Filed June 22, 1929

UNITED STATES PATENT OFFICE

HUGH P. PARIS, OF OAKLAND, CALIFORNIA

PORTABLE MATERIAL RECEIVING MEANS

Application filed June 22, 1929. Serial No. 372,970.

This invention relates to a discharge bin or storage hopper for receiving the contents of trucks and more particularly for receiving concrete and like material from a mixing device of relatively large capacity.

- In the handling of mixed concrete delivered in relatively large quantities at the place of its use, it has been the custom to move successive barrows or buggies beneath the discharge of the transporting vehicle and fill the same directly from the vehicle. This delays the departure of the vehicle and consequently reduces the maximum number of trips per day of the vehicle, reducing its efficiency. 10 At times the buggies may not be immediately available, which causes further delay. Another practice has been to discharge the material into a receptacle resting on the ground and to shovel or otherwise remove it therefrom at the time of its use, but this necessitates extra handling and increases the labor costs. 15

In my present invention I have provided a portable structure of the wheeled type capable of transporting from place to place and which, when in operative position, affords a means for receiving the concrete as discharged from the mixer and for elevating it to discharge into a hopper from which it may flow by gravity under control when needed. 20 I have further provided in this invention a means whereby the elevator is operated by power from the drive wheels of the mixer. Another provision of the invention is a sectional folding apparatus which, when being transported or not in use, may be folded into a relatively small compass. 25

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within 30 the scope of the claims may be resorted to without departing from the spirit or sacrificing any of the advantages of the invention. 40

In the drawings, disclosing the preferred embodiment of my invention—

50 Fig. 1 is a view in side elevation of my in-

vention with the parts illustrated in dotted lines when in folded position.

Fig. 2 is a view in top plan.

In the drawings—1 indicates a main frame supported by wheels 2 and provided at its forward end with a draft rig 3. Upwardly from opposite sides of the main frame extend conveyer supporting frame members 4 between which are fulcrumed at 5 the side members of a conveyer frame 6 disposed longitudinally over the main frame 1. At its ends the frame 6 mounts the rollers 7 over which operate a conventional belt 8. The rollers are intergeared through a bevel gear and shaft drive 9. Between the frame members 4 above the lower end of the top flight of belt 8 is an open bottomed material receiving hopper 10 discharging onto belt 8 and receiving material from the discharge opening of a concrete mixing cylinder 11 carried by a truck 12. 55 60 65 70

A power transmitting unit consisting of an open rectangular frame 13 is hinged at 14 to the forward end of the main frame 1. On the opposite ends of parallel shafts 15 are mounted the friction driven rollers 16 disposed in pairs at opposite sides of the frame. One shaft is connected by a belt 17 with a pulley on the end of one of the conveyer rollers 7 and the same transmits power from the truck drive wheels to the conveyer. Runways 18 are hinged to the opposite side edges of the free end of frame 13, affording a means for the truck power or drive wheels to run upwardly onto the rollers 16 and rest one between each pair, as in the drawings. 80 85

The forward set of rollers 16 may be temporarily locked from rotation by the insertion of a pin 19 into a recess 20 therein.

In operation, the truck is backed until the rear wheels rest one between each pair of rollers, as in the drawings, and with power applied to the truck wheels, driving the belt 8; the mixing cylinder is elevated dumping its contents into hopper 10, which delivers the material onto the upwardly travelling flight of the conveyer belt 8 for discharging into a hereinafter described bin. 90 95

A windlass 21 carried by the upper ends of frame member 4 connects through flexible 100

cables 22 with the forward end of frame 13 and its operation raises and lowers the frame, as in the drawings.

At the rear end of frame 1 is an open topped hopper 23 for receiving the concrete as it discharges from the conveyer. At its forward edge the hopper is fulcrumed at 23' and at its forward upper edge is connected through links 24 with the discharge end of the conveyer frame. Supporting legs 25 are provided at the rear lower edge of the hopper and the material is let from the hopper through controlled discharge outlets 26.

When in use, the apparatus is extended to the full line position, as in the drawings, and when not in use or during transportation, the parts are folded into the dotted line position. The forward pivotal movement of hopper 23 draws the discharge end of conveyer 22 downwardly into dotted line position, as in Fig. 1.

I claim:

1. A device of the class described comprising a main body portion affording a vehicle, an elevating conveyer carried thereby, a power receiving unit pivotally connected at one end of the vehicle to support and receive power from the driven wheels of a material transporting vehicle when in material dumping position, a connection between the power unit and the conveyer, a hopper hingedly connected at the opposite end of the vehicle to receive material from said conveyer, said power receiving unit and hopper capable of folding upon the opposite ends of the vehicle when not in use.

2. A device of the class described comprising a main body portion affording a vehicle, an endless conveyer tiltably mounted on the vehicle and extending longitudinally thereof, a power receiving unit pivotally connected at one end of the vehicle to support and receive power from the driven wheels of a material transporting vehicle when in material dumping position, a connection between the power unit and the conveyer, a hopper hingedly connected at the opposite end of the vehicle to receive material from said conveyer, said power receiving unit and hopper capable of folding upon the opposite ends of the vehicle when not in use.

3. A device of the class described comprising a main body portion affording a vehicle, an endless conveyer tiltably mounted on the vehicle and extending longitudinally thereof, a power receiving unit pivotally connected at one end of the vehicle to support and receive power from the driven wheels of a material transporting vehicle when in material dumping position, a connection between the power unit and the conveyer, a hopper hingedly connected at the opposite end of the vehicle to receive material from said conveyer, said power receiving unit and hopper capable of folding upon the opposite ends of the vehicle when not in use, with the discharge end of the conveyer received within said hopper.

4. A device of the class described comprising a main wheeled frame affording a vehicle, an endless conveyer carried above the same, means associated with the vehicle for supporting and receiving power from the driven wheels of a member discharging onto the conveyer for operating the same to convey the material upwardly and discharge the same from the end thereof an open bottomed hopper for receiving the material from said member and discharging same onto said conveyer, and a storage hopper associated with the vehicle for receiving the material from said conveyer.

5. A device of the class described comprising a main wheeled frame affording a vehicle, an endless conveyer pivotally carried longitudinally of and above the same, a power driven connection for operating the conveyer, a hopper pivotally mounted on the vehicle and into which the conveyer discharges, a link supporting connection between the conveyer and hopper, said link causing a pivotal movement of the conveyer on the pivoting of the hopper and its reception in a substantially horizontal position within said hopper.

6. A device of the class described comprising a main wheeled frame affording a vehicle, a conveyer carried thereby for receiving material and elevating the same, power receiving means hingedly connected to the forward end of the frame to receive power transmitted thereto and capable of upwardly swinging movement to overlie the frame when not in use, a connection between the power receiving means and the conveyer, and a hopper hingedly connected at the other end of the main frame for outward swinging movement beyond the end of the main frame when in use for receiving material from said conveyer, said hopper adapted for swinging movement to overlie the end of the main frame and rest thereon with the discharge end of the conveyer extending thereinto when not in use.

In testimony whereof I have signed my name to this specification.

HUGH P. PARIS.
